W. H. LANDING

LOCK

Filed Apr. 4, 1922

Lacey & Lacey, Attorneys

UNITED STATES PATENT OFFICE.

WILLIAM H. LANDING, OF SANTA ANA, CALIFORNIA, ASSIGNOR OF ONE-HALF TO
AL LINDSEY, OF SANTA ANA, CALIFORNIA.

LOCK.

Application filed April 4, 1922. Serial No. 549,583.

To all whom it may concern:

Be it known that I, WILLIAM H. LANDING, a citizen of the United States, residing at Santa Ana, in the county of Orange and State of California, have invented certain new and useful Improvements in Locks, of which the following is a specification.

This invention relates to door locks and has for its object the provision of means whereby a door may be securely fastened in closed position and cannot be opened except by manipulation of a key in a predetermined manner. The invention seeks to provide a lock in which the bolt will be normally retracted but may be projected into locking position by the use of a key, and a further object of the invention is to provide a combined latch and lock which may be released through the use of a single key but will require the operation of that key in two stages. The several stated objects and other objects which will incidentally appear are attained in the use of such a device as is illustrated in the accompanying drawings, and the invention resides in certain novel features which will be particularly pointed out in the claims following the description.

In the drawings—

Figure 1 is a perspective view of a lock constructed in accordance with my invention;

Fig. 2 is a sectional elevation of the same in position in a door with the latch and bolt both projected;

Fig. 3 is a view showing the position of the parts when the latch is withdrawn but the bolt is still projected;

Fig. 4 is a similar view showing both latch and bolt retracted.

Fig. 5 is a detail perspective view of the pivoted dog;

Fig. 6 is a detail perspective view of the slidable dog.

The lock case 1 is illustrated as of the form adapted for a mortise lock and is preferably cast in one piece with the exception of the closing face plate 2, as will be readily understood. The lock case receives and slidably supports a latch 3 and a bolt 4 and also receives and rotatably supports a knob spindle 5 which is disposed transversely in the lock between the latch and the bolt. Within the lock case, the knob spindle is equipped with a pinion 6 meshing

with a rack 7 on the under side of the latch, and a dog 8 is pivotally mounted within the lock case in position to engage said wheel 6 and normally hold the latch projected by preventing rotation of the pinion. The latch is constructed in its rear end portion with a longitudinal slot or notch 9 in which is housed a retractile spring 10 having one end secured to a post 11 fixed on the back of the lock case and its opposite end held by a post 12 in the forward end of the slot 9, as clearly shown. When the dog 8 is released from the pinion 6, the spring 10 at once retracts so as to withdraw the latch, and manipulation of the knob spindle is not necessary. When it is desired to project the latch into engagement with the lock strike or keeper, the knob spindle is rotated in the proper direction to impart movement of the latch through the engagement of the pinion 6 and the rack 7 in an obvious manner. During this movement of the wheel 6, the teeth of the same will ride under the dog 8, which is yieldably held in engagement with the wheel by a spring 13 coiled around the pivot of the dog and having one end bearing upon the dog and its opposite end bearing upon a lug 14 provided in the lock case.

The bolt 4 is also provided in its rear end portion with a longitudinal slot or notch 15 and a retractile spring 16 is housed within said notch, one end of said spring being held by a fixed lug 17 on the back of the lock case and its opposite end being connected with a lug 18 at the front end of the notch 15. The bolt is provided on its upper side with a lug or projection 19 which may be engaged by a key when the bolt is to be projected and the outer or forward movement of the bolt is limited by the said lug 19 impinging against a stop lug 20 within the lock case. The rear end of the bolt is adapted to be engaged by the lower end 21 of a dog 22 slidably mounted upon the back of the lock case and provided with a cylindrical stem 23 playing in the lug 14. A pin or other abutment 24 is provided at the upper end of the stem 23 to engage the lug 14 and thereby limit the downward movement of the dog, and a spring 25 is coiled around the stem between the said lug 14 and the shoulder 26 of the dog to normally project the dog downward. When the dog is at the lower limit of its movement, as shown

in Figs. 2 and 3, the rear upper corner of the bolt will bear against the vertical face of the dog at the lower end thereof and will, therefore, be held in a projected position. 5 If the key, however, be inserted in the lock case so that it occupies a horizontal position, the rotation of the key will lift the dog 22 from its engagement with the bolt, whereupon the spring 16 will at once retract 10 and withdraw the bolt. The lug 19, however, will be moved against the stem of the key through the retracting movement of the bolt and, therefore, the bolt cannot be fully retracted until the key is withdrawn. When 15 the bolt is to be again projected, the key is inserted in a vertical position and is then rocked so that it will act upon the lug 19 and project the bolt, the dog 22 automatically sliding downwardly and assuming its 20 position in rear of the bolt.

It will be readily noted that the keyhole 27 is cruciform so that the key may be inserted in either a vertical or a horizontal position. When it is desired to release the 25 dog 8 from the wheel 6, the key must be inserted in a vertical position and rocked, as indicated in Fig. 3, so as to bear upon the lower end of said dog and thereby rock the same so that its upper end will be released from the wheel. The key must be held in engagement with the dog until the 30 latch is fully retracted. The parts are so proportioned that when the key is in the position indicated in Fig. 3, it cannot engage the vertically movable dog to release the bolt and when the bolt is retracted the key cannot be inserted in a horizontal position. Therefore, it is necessary in opening 35 the door to first release the latch and then withdraw the key and reinsert it so as to lift the dog 22 and permit the bolt to be retracted. In locking the door, the bolt must be first projected by inserting the key in a vertical position with its stem at the upper 40 end of the vertical branch of the keyhole in order to first project the bolt. After the bolt has been projected, the key may then be inserted in a vertical position so as to rock upon the lower end of the vertical 45 branch of the keyhole and release the dog 8, whereupon the spring 10 will at once project the latch. 50

It will be readily noted that I have provided an exceedingly simple lock composed 55 of few parts which may be, therefore, produced at a low cost and which will be found highly efficient in use.

Having thus described the invention, what is claimed as new is:

1. In a lock, the combination of a lock 60 case provided with a cruciform keyhole, a latch mounted in the lock case above said keyhole, a bolt slidably mounted in the case below the keyhole, said bolt when retracted being adapted to partly cover the keyhole, 65 means for projecting the latch, yieldable means for holding the latch projected, and yieldable means for holding the latch and the bolt normally retracted, the means for holding the latch projected being releasable 70 by a key fitted in the keyhole in one position and the bolt being constructed to be projected by the same key inserted in the keyhole in another position.

2. The combination of a lock case, a key- 75 projected bolt slidably mounted therein, yieldable means for holding the bolt normally retracted, a dog slidably mounted in the lock case, yieldable means for automatically projecting the dog into engagement with the rear end of the bolt as the bolt is projected, and means for limiting the projecting movement of the bolt.

3. The combination of a lock case, a bolt 80 slidably mounted therein and provided on its upper side near its inner end with a lug 85 to be engaged by a key to permit the bolt to be projected, a retractile spring connected with the lock case and the bolt to hold the bolt normally withdrawn, a vertically movable dog slidably mounted upon the lock case and adapted to engage the rear end of the bolt in the projected position of the latter, 90 yieldable means holding the dog to the bolt, and a key insertible into the lock case and 95 engageable with the bolt in one position to project the same and engageable with the dog in another position to release the same and permit retraction of the bolt.

4. The combination with a lock case, of 100 a latch mounted slidably therein and provided with a rack on its lower edge, a knob spindle rotatably fitted in the case, a pinion on said spindle meshing with the rack on the latch, a retractile spring connected with 105 the latch and with the lock case to normally hold the latch retracted, a dog pivotally mounted within the lock case and yieldably engaging the pinion, and a key to be inserted in the lock case and engageable with 110 the dog to release the same.

In testimony whereof I affix my signature.

WILLIAM H. LANDING. [L.S.]
